Primary Examiner — Catherine S Posthauer*Assistant Examiner* — Christine Marie Achen Zimmerman
(74) *Attorney, Agent, or Firm* — Lowenstein Sandler LLP(57) **CLAIM**

The ornamental design for a juicer apparatus, as shown and described.

DESCRIPTION

FIG. 1 is a perspective view of a juicer apparatus, showing my new design;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof; and,

FIG. 7 is a bottom plan view thereof.

The portions of the juicer apparatus shown in broken lines form no part of the claimed design.
